MEANS FOR STOPPING THE FLOW OF
FLUIDS UNDER PRESSURE

Chester C. Hosmer, Long Beach, Calif.

Application January 19, 1931, Serial No. 509,755

7 Claims. (Cl. 251—51)

This invention relates to devices for stopping the flow of a fluid, either gas or a liquid, or a mixture of the same, when under heavy pressure. More specifically, it relates to valves for checking or stopping the flow of oil or gas, or both oil and gas, from a well, and it will be so described herein. In drilling, or in the operation of oil wells, it not infrequently happens that gas, or oil under a heavy gas pressure, breaks into the well and spouts out of the same. Usually the pressure is very great and, under the most favorable conditions, it is difficult to stop or check the flow with devices now available. The gas and oil are liable to ignite and, when this happens, it is indeed a problem as to how the flow can be stopped. It has been proposed to employ a sliding valve and to control it from a remote point by hydraulic or pneumatic means. But such a valve has been unsatisfactory in use for the reason that, in order to stop the flow, it is necessary that the valve be packed so as completely to close the well casing and, owing to the tremendous pressure below the valve, it is almost impossible to slide it into its closed position. If it be forced while subjected to this pressure the packing is generally destroyed or is so damaged that it is incapable of functioning effectively.

It is the object of my invention to provide a valve which can be opened and closed against any pressure encountered in an oil well, and that without damage to the packing with which the valve is provided. While my present preferred embodiment of the invention is as shown in the accompanying drawing and described specifically herein, it is obvious that changes in details are possible, and I desire it understood that the accompanying claims are not intended to be limited to the details shown and described any farther than their specific terms require.

40. In the drawing, Fig. 1 is a plan view showing the upper face of the valve casing partially broken away, the valve being in its closed position; Fig. 2 is a longitudinal, vertical section through the center of the valve structure, as on line 2—2 of Fig. 1; Fig. 3 is a section through the casing and valve taken on the line 3—3 of Fig. 1; Fig. 4 is a section on line 4—4 of Fig. 1; Fig. 5 is a fragmentary perspective view showing a modified form of connection between the valve and its operating rod; Fig. 6 is a fragmentary sectional view showing the packing member carried by the valve casing; Figs. 7 and 8 are fragmentary sectional views showing modifications of the means for depressing the valve against the pressure beneath it.

55. In Fig. 2 a portion of the well casing is desig-

nated 5. To it is connected, through any suitable member 6, the casing of a slide valve 7, said casing being shown as rectangular and as comprising a lower member 8 with upwardly extending side and end flanges and a top member 9, the latter being securely bolted to said flanges, as shown. Within the flanges and between the members 8 and 9 is the valve chamber 10, the upper surface of which is designated 9a. In line with the well casing, the said members are provided with apertures 11 and 11a, respectively, thereby forming a passage for the gas and oil when the valve 7 is open. In the drawing, except in Fig. 6, the valve is shown in its closed position; but the chamber 10 is elongated and the valve is opened by moving it to the right to substantially the end of the chamber. This movement is effected through any suitable means, as by a rod 12 which is attached to the right-hand edge of the valve and is extended through the corresponding end flange of the casing member 8, being preferably surrounded by a stuffing gland 13 to prevent leakage of the gas or oil. In practice, the rod 12 would be moved preferably by fluid pressure, as by water, air or steam, which may be controlled from a remote point. This, however, forms no part of my present invention and further description and illustration are deemed unnecessary.

Within a circular groove in the upper surface of the valve 7 is a packing member 14. This may be composed of any suitable material or combination of materials. It is in the form of a continuous ring with an inner diameter substantially equal to that of the aperture 11a in the casing member 9. While I prefer to use a ring-shaped packing 14, as shown, other forms of packing may be employed, it simply being required that it close against the surface 9a about the aperture 11a. It is obvious that it may be a flat disk or plate set into the upper surface of the valve. When the valve is closed, as shown, this packing member surrounds the said aperture, and the pressure below the valve compresses the packing and thus shuts off all flow of fluid of any kind. This pressure is supplemented in a slight degree by a pair of flat springs 15 on the under side of the valve, there being a spring adjacent each of the side edges thereof, as indicated in Fig. 1. The principal function of these springs, however, is to support the valve from the upper surface of the casing member 8 as the valve is moved to open or close it. Since, as will be shown, the valve is movable vertically to a slight extent, these springs are hooked at their ends over pins

in the valve, the hooks being open to permit the ends of the springs to slide thereon, as will be clear from Fig. 4.

Mounted for rotation in a pocket 16 adjacent each corner of the valve is a wheel or roller 17. These wheels are of such size as to roll against the lower surface 9a of the casing member 9 when the valve is moving and to depress the valve far enough to maintain the packing member 14 out of contact with that surface. They therefore constitute roller bearings for the valve and also means for depressing the latter to hold the packing member away from the surface 9a. As will be noted from Fig. 1, the wheels at one end of the valve are spaced differently from those at the other end. The reason for this will be stated hereinafter.

In order to permit the valve to rise and compress the packing member about the aperture 11a, as shown in Fig. 2, the casing member 9 is provided with a series of pockets 18 in its under side, there being a pocket for each of the wheels 17. These pockets are so placed that the wheels snap upwardly into them when the valve has been moved in closing until the packing is substantially in position to surround the aperture 11a, and they are of sufficient depth to allow the packing to be compressed against the surface 9a. In operation, therefore, the wheels roll upon the surface 9a with but little resistance, holding the packing out of engagement with said surface until the end of the closing movement is substantially reached, when the wheels roll into the pockets and allow the valve to rise to close and compress the packing. Thus, with little effort and without damage to the packing, the passage for the gas and oil through the aperture 11a is completely closed. However, as a practical matter in the operation of oil wells, it is necessary to provide means for permitting the oil and gas to escape from beneath the valve. For that purpose, the flanges of the casing member 8 are provided with apertures for relief pipes 19 and 19a which are each furnished with valves, not shown, for controlling the flow of the fluid and relieving the pressure in the well. The valve 7 is also provided with recesses 20 and 20a in its sides to register with the respective relief pipes when the valve is closed, as indicated in Fig. 1. While those pipes and recesses may be variously placed with reference to the aperture 11, I prefer to locate them on the transverse axis through the said aperture.

For forcing the packing away from its seat to relieve the gas pressure or in preparation for opening the valve, I provide in each of the pockets 18 a pressure block 21 which is swiveled to the lower end of a screw or bolt 22 threaded through the upper member 9 of the valve casing, a suitable packing gland surrounding the screw to prevent leakage of gas or oil. By turning these screws downwardly, the pressure blocks are caused to push the wheels 17 out of their respective pockets 18. As soon as the packing is separated from the surface 9a, the pressure fluid may escape and the separation may be made sufficient as materially to reduce the pressure below the valve. As soon as the wheels are lowered until their upper surfaces are substantially flush with the said surface, the valve may be readily opened.

The rod 12 may be secured to the valve 7 in any suitable way which will permit the valve to move up and down. As shown in Figs. 1 and 2, the valve 7 is provided with a lug 23 having parallel sides. Side links 24 are pivoted to the said

lug and to the adjacent flattened end of the rod 12, it being understood that the rod does not partake of the vertical movement of the valve. In Fig. 5 I have shown a modified form of connecting means between the rod and the valve, in which a plate 25 is secured to the end of the rod and is adapted to play up and down in a slot in the valve near its edge, the said edge being slotted vertically at 26 to permit the valve to move relatively to the end of the rod.

The wheels 17 are differently spaced on the valve in order that each wheel may run on its own track. If they were spaced alike, a wheel would snap into a pocket intended for another wheel and before the valve had reached its closing position.

Fig. 6 shows the packing ring 14a seated within an annular groove in the casing member 9 concentric with the aperture 11a. The valve 7a is in its open position, being held below the plane of the lower face of the packing by the roller 17 which is in contact with the surface 9a. As in the structure of Figs. 1 to 4, the rollers snap into pockets in the member 9 when the valve is substantially centered below the aperture 11a to compress the packing member. In this modification, the upper surface of the valve would be plain in those portions which engage the packing.

In Fig. 8 I have shown a modified means for forcing the wheels 17 out of the pockets. The valve 7b is provided with a cam surface 27 with which engages the tapered or cam-shaped end of a screw 28 which projects through the flange of the casing member 8. As illustrated, the screw has been turned until the valve is almost in its lowest position so that it may be drawn out. As many cam surfaces and screws may be employed as may be needed to move the valve bodily away from the surface 9a.

Fig. 7 shows a still further modification of the means for forcing the wheels out of their pockets. In it, the pockets 18a are rounded or tapered and the wheel is forced to roll out of the same by one or more pushing screws 29 which extend outwardly through the flange of the member 8.

By the comparatively simple and inexpensive structure thus described, the flow of gas, or oil and gas, can be effectively controlled without damage to the packing and irrespective of the high pressure to which the valve may be subjected.

Having thus described my invention, I claim:

1. A means for stopping the flow of a fluid under pressure comprising a casing having two spaced and parallel surfaces forming the opposite sides of a valve chamber and having a passage for fluid therethrough, a valve slidable within said chamber into and out of register with said passage, said valve being subjected to fluid pressure on one of its sides, means for sliding said valve, means for holding the valve out of contact with said surfaces throughout substantially its entire sliding movements, means provided in one of said surfaces for permitting the valve to move automatically under the fluid pressure toward that surface when it is slid into register with said passage to close the latter, and means for positively forcing the valve away from the last mentioned surface preparatory to starting the opening movement of the valve.

2. A structure as set forth in claim 1 having a packing member so positioned as to be compressed between the valve and the opposing surface of the casing when the valve moves toward said surface, whereby the passage is closed.

3. A means for stopping the flow of a fluid under

pressure comprising a casing having two spaced
and opposing members forming a valve chamber, the wall having the said pockets therein, means
for moving the valve longitudinally into and out

said casing having a passage for fluid therethrough
and one of said members having a plurality of
pockets opening into said chamber, a valve in said
chamber, said valve being subjected to fluid pres-
sure on one of its sides, means for moving said
valve into and out of register with the said pas-
sage, rollers carried by said valve and in rolling

10 contact with the inner surface of the casing mem-
ber having the pockets therein, said rollers hold-
ing the valve away from said casing member and
against the fluid pressure while the valve is out
of its closing position and the rollers and the

15 pockets being so positioned that the rollers are
snapped into said pockets due to the pressure
of the fluid when the valve is brought into reg-
ister with said passage, whereby the valve is
brought into contact with the casing member to

20 close said passage, and means for relieving the
pressure against the valve when said passage is
closed.

4. A structure as set forth in claim 3 having
a packing member that is compressed between the
25 valve and casing about said passage when the
rollers snap into their respective pockets.

5. In combination, a valve casing having a fluid
passage therethrough and a series of pockets in
30 one of its interior walls, a valve within said casing,
said valve being subject to the pressure of the fluid
tending to move the valve transversely and toward

of register with the fluid passage, a plurality of
rollers carried by said valve and in rolling con-
tact with the valve casing for holding the valve
away from the casing while it is out of register
80 with said passage, said rollers being adapted to
roll into the pockets in said valve casing when
the valve is brought into register with said pas-
sage, whereby the pressure of the fluid causes the
rollers to enter their respective pockets and the
85 valve to be brought into contact with the casing
about said passage to stop the flow of the fluid
therethrough, and means independent of the lon-
gitudinal movement of the valve for forcing the
rollers out of their pockets against the pressure of
90 the fluid and into position for rolling on the valve
casing, whereby the valve may be moved longi-
tudinally to open the passage.

6. A structure as set forth in claim 5 in which
the means for forcing the rollers out of their
pockets comprises a pressure block for and within
each of the said pockets and screws passing out-
wardly through the casing and contacting said
blocks for pressing the respective blocks inwardly
100 against the rollers.

7. A structure as set forth in claim 5 in which
the valve is provided with means for yieldingly
holding the rollers in contact with the surface of
the valve casing upon which they roll. 105
